UNITED STATES PATENT OFFICE.

RICHARD MARTIN, OF SWANSEA, AND JOHN ISAAC RICHARDS, OF YSTALYFERA, NEAR SWANSEA, WALES.

APPARATUS FOR USE IN THE TREATMENT OF PULVERULENT OR GRANULAR MATERIALS WITH GASES.

Application filed February 26, 1921. Serial No. 448,221.

To all whom it may concern:

Be it known that we, RICHARD MARTIN, a subject of the King of Great Britain and Ireland, and residing at Exeter Villa, Uplands, Swansea, in the county of Glamorgan, Wales, and JOHN ISAAC RICHARDS, a subject of the King of Great Britain and Ireland, and residing at Upper Clay Works, Ystalyfera, near Swansea, in the county of 10 Glamorgan, Wales, have invented certain new and useful Improvements in Apparatus for Use in the Treatment of Pulverulent or Granular Materials with Gases, of which the following is a specification.

15 This invention relates to apparatus for use in the treatment of pulverulent or granular materials in a current of gas and is particularly concerned with the roasting of ores and the like.

20 The object of the invention, broadly stated, is to provide improved means for conveying the granular or pulverulent material treated through a chamber as, for instance, a roasting furnace, in which the 25 material is subjected to the action of a gas current and to expose fresh surfaces of the material therein to the action of the heated gases.

A further object of the invention is to 30 provide an improved furnace adapted for use in roasting ores and the like of the kind comprising a plurality of hearths or floors arranged one above another and openings adjacent to alternate ends of these floors or 35 hearths whereby the material treated may be transferred from one floor on to the floor or hearth situated next below, and means adapted to cause the ore to travel over these floors or hearths in succession.

40 According to the invention, a member provided with a scraper element and a plurality of plough elements is caused to travel over the floor or hearth on which the granular or pulverulent material is deposited, alternately in a backward and forward direction and means is associated with the said member whereby the motion of the said member causes the scraper element or the plough elements as the case may be to be 45 brought into operation to convey the material over the floor or hearth or to expose

fresh surfaces of the material to the action of the current of gas.

Thus in accordance with the invention the member provided with the scraper blade 55 and the plough elements may be pivotally connected to the means whereby the said member is caused to travel backward and forward within the chamber and associated with means adapted to bear upon the floor 60 or hearth thereof or the material thereon and to rotate the member about its pivotal connection to bring the scraper blade or ploughs, according to the direction in which the 65 said member is moving, into position to operate upon the material:

The means adapted to bear upon the floor or hearth may be constituted by a member, such as a segment or sector-shaped member, the curved face of which is arranged adjacent to the floor or hearth so that the friction between the curved face and the hearth will cause the member provided with a 70 scraper element and plough elements to be rotated about its pivotal connection with the means whereby it is caused to travel through the furnace when the direction of its motion is changed and to maintain the scraper or ploughs in position to operate 75 upon the material.

One or more members provided with scraper and plough elements may be arranged at suitable distances in front of one another in association with each floor or 80 hearth.

The scraper may be in the form of a blade extending substantially across the whole width of the chamber and secured at points at suitable distances apart to brackets which are connected to a bar as, for instance, by passing the lug of each of these brackets through a hole in the bar and passing a pin through a hole provided for this purpose in the lug, or they may be provided with sleeves adapted to be slipped over the bar, and the scraper blade may be of such depth that a portion of the material operated upon will pass or flow over the top edge thereof. The ploughs may be similarly secured to brackets secured to the bar 95 which is provided with pivots at its ends, journaled in holes provided in blocks se-

cured to the means whereby the combined scraper and plough element is caused to travel over the floor or hearth.

For causing the member provided with the scraper element and plough elements to travel over the floor or hearth, any suitable means may be employed,

For instance, the member provided with the scraper element and plough elements

10 may be secured to flexible members, such as chains or metallic bands, or ropes arranged to pass through the furnace from end to end and to be set in motion by suitable means in order that the combined scraper and plough elements may be moved alternately in a backward and forward direction.

When flexible members such as chains or bands are employed for this purpose, they may be passed over guide sprockets or pulleys arranged adjacent to the front or rear wall of the furnace and thence in an upward or downward direction over suitable sprockets or pulleys adapted to impart to them the required motion.

25 This arrangement, as will be recognized, results in economy of space as compared with the arrangement in which the combined scraper and plough elements are secured to bars which are adapted to cause 30 these elements to travel over the floors or hearths.

One construction in accordance with the invention is illustrated by way of example in the accompanying drawings, in which:-

35 Figure 1 is a section through a furnace provided with devices in accordance with the invention, and

Figure 2 is a corresponding plan view.

In the drawings, 1 are the chambers of the 40 furnaces, 2 the floors thereof, 3 apertures in the floors through which the material passes from floor to floor, 4 the scraper blades extending across the whole width of the chambers, 5 the plough element, 6 the 45 brackets to which the scraper blades and plough members are secured to the bars 7 which for the greater portion of their length are of rectangular cross-section and engage holes in these brackets of similar form. 8 50 are frames provided with bearings, 9, 9^a in which the ends of the bar which at this position is of circular cross-section, are engaged. The frames are connected with wire cables or bands 10 when necessary formed, 55 as are the other portions of the device which are subjected to a high temperature, of suitable heat resisting alloys adapted to withstand temperatures of 1000° Fahrenheit, which pass over jockey pulleys 11 associated 60 with tensioning means 12 arranged on one side of the furnace and with bands or cables 13 passing over pulleys 14 secured on shafts 15 which are for suitable periods of time rotated in a clockwise and anti-clockwise direction to secure the desired reciprocatory

motion of the scraper and plough elements, spur wheels 16 being mounted on said shafts and engaging spur wheels 17 secured on shafts 18 to secure the desired motion of the several scraper and plough elements in 70 unison.

Having now described our invention, what we claim as new and desire to secure by Letters Patent is:-

1. Improved means for conveying granular or pulverulent material through a chamber as, for instance, a roasting furnace, in which the material is subjected to the action of a gas current, and for exposing fresh surfaces of the material therein to the action of the heated gases, comprising a member provided with a scraper element and a plurality of plough elements, means whereby said member is caused to travel alternately in a backward and forward direction through the 85 chamber and means whereby motion in the one direction causes the scraper element to be brought into position to operate on the material on the floor of said chamber and convey material therethrough and motion in 90 the other direction removes the scraper element from the said position and brings the plough elements into position to operate on the material on the floor of the chamber in order to expose fresh surfaces of the material 95 to the action of the current of gas.

2. Improved means for conveying granular or pulverulent material through a chamber as, for instance, a roasting furnace, in which the material is subjected to the action of a gas current, and for exposing fresh surfaces of the material therein to the action of the heated gases, comprising a member provided with a scraper element and a plurality of plough elements, means whereby said member is caused to travel in a backward and forward direction through the chamber, a pivotal connection between the member and said means and members adapted to bear upon the material on the floor of the chamber and by frictional contact therewith to rotate the member provided with a scraper element and plough elements to bring the scraper blade or ploughs into position to operate on the material.

3. Improved means for conveying granular or pulverulent material through a chamber as, for instance, a roasting furnace, in which the material is subjected to the action of a gas current, and for exposing fresh surfaces of the material therein to the action of the heated gases, comprising a member provided with a scraper element and a plurality of plough elements, means whereby said member is caused to travel in a backward and forward direction through the chamber, a pivotal connection between the member and said means, sector-shaped members having their curved faces directed to the floor of the chamber adapted to bear upon the material 120

on the floor of the chamber and by frictional contact therewith to rotate the member provided with a scraper element and plough elements to bring the scraper blade or ploughs into position to operate on the material.

4. Improved means for conveying granular or pulverulent material through a chamber as, for instance, a roasting furnace, in which the material is subjected to the action of a gas current, and for exposing fresh surfaces of the material therein to the action of the heated gases, comprising a member provided with a scraper element in the form of a blade extending substantially across the whole width of the chamber, a plurality of brackets securing the blade to the member,

plough elements, brackets securing said plough elements to the member, means whereby said member is caused to travel in a backward and forward direction through the chamber, a pivotal connection between the member and said means, and members adapted to bear upon the material on the floor of the chamber and by frictional contact therewith to rotate the member provided with a scraper element and plough elements to bring the scraper blade or ploughs into position to operate on the material.

In testimony whereof we have signed our names to this specification.

RICHARD MARTIN.

JOHN ISAAC RICHARDS.
